UNITED STATES PATENT OFFICE

YOUNG HO KOUN, OF NEW YORK, N. Y.

AUTOMATIC CONTROL SYSTEM FOR AEROPLANES

Application filed April 28, 1931. Serial No. 533,497.

The invention relates to aeroplanes and its object is to provide a stabilizing means for controlling the aeroplane in the air.

Another object of the invention is to provide a stabilizer for aeroplanes adapted for hand control operation and self-control operation so that it may operate with hand control or without, thus providing for automatic operation.

10. Additional objects of the invention will become more fully known by the following specifications, in which the preferred form of the invention is described.

In the drawings similar reference characters refer to similar parts in all the views, of which

Figure 1 is a plan view of a monoplane equipped with a stabilizing device mounted in tubes on the fuselage.

20. Figure 2 is a side view of Figure 1.

Figure 3 is a diagrammatic plan view of the stabilizer means and wiring.

Figure 4 is automatic altitude control stick shown in section.

25. By referring to the drawings it will be seen that a monoplane is illustrated, but it will of course be understood that the invention may be used on a biplane or any other type of aeroplane. It should also be understood that 30 the device can be mounted on the wing or in the wings instead of on the fuselage. The device may be arranged to occupy one tube or box instead of three tubes.

Briefly described, my invention comprises a 35 good conductive metal weight firmly mounted on good conductive metal rolls. The weight with the rolls is mounted on good conductive metal rails which are built into an insulated tube and mounted on both sides of the fuselage horizontally.

The tubes are parallel to the wings and laterally disposed thereto, so that the tube and wing coincide in their motions. The rails are built with a sloping or inclined plane, 45 just steep enough so as to allow the weight to move along the plane when the wing is tipped, and to move back into its original position when the wings are on even level and the aeroplane is in normal flying position.

50. The altitude control system works on the

same principle: When the aeroplane is tilting towards the front; the weight on the rails moves up the inclined plane, and when the plane is in horizontal position the weight moves back to its original position and rests 55 on the base of the inclined plane.

The altitude controlling tube is mounted on the fuselage longitudinally thereto and is parallel to the front part of the fuselage and 60 to the propeller shaft.

The device described herein is for the control of an aeroplane either by hand or by automatically or semi-automatically operating.

65. The device controlling the wings when seen in the direction of flight, is constructed as follows:

As illustrated, an aeroplane 10 of any conventional type has suitably attached to its fuselage in rear of its wings 11 equipped with 70 the customary ailerons 12 to both sides of the fuselage, a cross-wise arranged tube or container 13 provided with doors 14.

The bottom of the tube 13 carries an insulating rubber pad 15 acting simultaneously 75 as shock absorber.

Bottom pad 15 carries in the tube on one side of the fuselage near its inner end a substantially wedge-shaped rubber body 16 having a stop 16' and juxtaposed to a metal element 17 near the outer end of the tube and both carrying a metal rail 18 on which the rollers 19 of a carriage 20 are running.

The pad 15' forming the bottom of tube 85 13 on the opposite side of the wing carries also a rubber body 16'' which is substantially wedge-shaped and with its pointed end is directed towards the inner end of the tube, while acting as shock absorber 16'''.

Its opposite end is juxtaposed to a metal element 17' and both elements 16'' and 17' carry the rail 18' on which run the wheels 19' of a carriage 20'.

A wire 21 connects the metal body 17 with 95 one pole of a pair of solenoids or electromagnets 22 the other pole of which is connected by a wire 23 to a battery 24 and by a wire 25 to a switch 26.

The carriage 20 is connected by a wire 27 100 to switch 28. Oppositely disposed to the

poles of the electromagnets 22 is an armature 29 normally spaced from said poles and connected by means of a spring 30 to the stick 31 pivotally attached as at 32 in the cockpit of the aircraft and balanced by springs 33, 34.

An armature 35 is attached by means of a spring 36 to stick 31 on the opposite side thereof, and is normally spaced from the 10 poles of an electromagnet 37.

Electromagnets 37 are connected by means of wire 38 to battery 24, and by means of wire 39 to the metal piece 17', while the carriage 20' is connected by means of a wire 15 40 to switch 28 closing a circuit over the wires 41, 42, grounded at 43, 44, on the fuselage of the plane.

In the center of the fuselage a tube 45 is provided longitudinally extending to the 20 fuselage of the airplane and having on one side a rubber pad 46 carrying on its outer end a wedge-shaped rubber body 47 having a shock absorbing abutment 48. Juxtaposed to rubber body 47 within tube 45 is a metal 25 element 49 and carrying a rail 50 on which run the wheels 51 of a carriage 52. A wire 53 connected to said metal body is grounded as at 54, while a wire 55 connects the carriage with switch 26. The switch 30 is connected by means of wire 25 to a pair of electromagnets 56 connected by wire 57 to the battery 24.

An armature 58 is connected by means of a spring 59 to stick 60 controlled by a spring 35 61, and the controls for the elevator control gear are operated by means of member 62 connected by means of member 63 to the elevators 64, 65.

The device operates as follows: Assuming 40 that during the flight the right hand wing of the plane sinks elevating the left hand wing. This will slide carriage 20 from its position on the insulated member 16 onto the metal member 17 to close a circuit across 45 wire 21 to solenoids 22, wire 23 to battery 24 and wire 27 to switch 28. The electromagnets will be energized to attract armature 29 and move stick 31 to the right. This stick is in the usual manner not forming 50 part of my invention connected to the means controlling the aileron 12 so as to turn aileron 12 on the left wing upward to offer resistance to the air which will tend to lower the left hand wing thus carrying the right hand wing 55 upward until the aircraft is balanced again, the carriage 20 sliding back into its normal position on insulation 16 will open the circuit, de-energizing the electromagnets so that spring 30 can now guide the stick 31 60 into its normal position.

The same cycle of operations will take place if the left hand wing is lowered and the right hand wing elevated. If the plane 65 goes into a tail spin, carriage 52 will close in a similar manner a circuit over electro-

magnets 56 and the armature 58 will move stick 60 to operate the raising elevators 64, 65, so as to balance the craft again.

It will be understood that I have disclosed the preferred form of my device only, and that I may make such changes therein as come within the scope of my invention as claimed, without departure from my invention.

Having thus described my invention what 75 I claim as new and desire to secure by Letters Patent is:

1. In a device as described, a tube transversely arranged to the fuselage of an aircraft behind its wings, and comprising duplicate circuit closers one for each wing, each consisting of a carriage normally resting on a rail on an insulated member adapted to slide onto a metal member over which said rail extends, upon the lowering of the respective wing to close a circuit, solenoids energized upon the closing of the circuit, a spring controlled stick controlling the ailerons of the craft, and armatures to be attracted by the energized solenoids, means connecting stick and ailerons to raise the aileron on the raised wing and to lower the aileron on the lowered wing stabilizing the aircraft.

2. In an aircraft including its fuselage, a casing longitudinally arranged in said fuselage, an insulator member in said casing, a metal member arranged in juxtaposition thereto, a rail, covering said insulated and metal member, a carriage running on said rail normally held on the insulated member, running on said rail to engage said metal member, a circuit in which said metal member and carriage are located to be closed upon the arrival of said carriage on said metal member by the raising of the aircraft's tail, a stick, connections between said stick and the elevators, an armature connected to said stick, solenoids adapted to be energized upon the closure of the circuit to attract said armature to operate said stick and its connections to the elevators to raise the same for balancing the craft about to go into a tail-spin.

3. In an aircraft, means for automatically stabilizing the same when tilting from the horizontal plane of flight, said means comprising casings, each having an insulated bottom, an insulation member on said bottom, a conductor member juxtaposed thereto, a stop on said insulation member, a rail, and a carriage running over said rail, circuits in which said conductor member and carriage are located adapted to be closed upon the moving of said carriage onto the conductor member under the influence of the tilt of a wing and the tail piece of the aircraft, solenoids adapted to be energized by the closure of the circuits, armatures adapted to be attracted by said solenoids upon their energization, a stick, connections between said stick and said armatures to draw the stick 130

in one direction upon the closing of the circuits, connections between the stick and the ailerons and elevators, adapted to be operated by the displacement of said stick to 5 raise the aileron on the raised wing and to lower the aileron on the lowered wing to balance the craft by the air-resistance against said ailerons, and said elevators.

4. In an aircraft, means for automatically 10 stabilizing the same when tilting from the horizontal plane of flight, said means including a stick, connections between said stick and the ailerons and elevators of the plane, circuits, means for automatically closing 15 said circuits by the inclination of the plane, solenoids in said circuits adapted to be energized upon the closing of said circuits to attract said armatures, springs for connecting said connections to the stick to 20 draw it with the armature towards the solenoids to operate the ailerons and elevators to balance the craft, and springs for controlling the movements of said stick, and means for automatically controlling the auxiliary 25 cable for the control of the rudders.

In testimony whereof, I affix my signature.
